SPECIFICATION forming part of Design No. 20,285, dated November 11, 1890.

Application filed October 10, 1890. Serial No. 367,637. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The accompanying photograph is a face view of a carpet showing my new design.

My design consists of the body A and the border B. The body A is composed of large and small groups of leaf forms resembling maple-leaves and of branch forms, all lying on a shaded groundwork of leaf form. The

border B is composed of an inner margin having deep serrations, a middle portion of large and small groups of forms resembling maple-leaves and of branch forms, all lying on a shaded groundwork of leaf forms, and an outer margin having leaf forms, among which may be seen small gem ornamentations.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.
